UNITED STATES PATENT OFFICE.

GROVER CLEVELAND TRUSLOW, OF DRAPER, NORTH CAROLINA.

MIXER.

Application filed May 7, 1923, Serial No. 637,314. Renewed September 13, 1924.

To all whom it may concern:

Be it known that I, GROVER C. TRUSLOW, a citizen of the United States of America, and a resident of Draper, in the county of Rockingham and State of North Carolina, have invented a new and Improved Mixer, of which the following is a description.

This invention relates to an apparatus for mixing fibers of different characters, such as, for example, as cotton and wool, or fibers of different colors.

The invention particularly relates to an apparatus which blows and distributes the fibers over a floor to form a bed of fibers. Usually the fibers are caused to be blown by means of a blower, fan, or like device and by confining the air current by the pipe line or the like connected to a picker or preparatory machine whence the fibers are delivered to the blowing device and thence through the mixing and bedding machine.

The present invention is intended more particularly as an improvement on the mixing apparatus forming the subject matter of United States Letters Patent, No. 1,399,590, granted to me December 6, 1921.

The general object of the present invention is to provide a mixing apparatus which will throw the fibers being mixed or bedded a greater distance so that a larger bedding room may be used and the maximum amount of material can be bedded.

The nature of the invention and its distinguishing features and advantages will clearly appear as the description proceeds.

Reference is to be had to the accompanying drawings forming a part of this specification, it being understood that the drawings are merely illustrative of practical examples of the invention.

Figure 1 is a view partly in elevation and partly in vertical section of a mixing apparatus embodying my invention in one form;

Figure 2 is a detail in sectional plan view as indicated by the line 2—2, Figure 1;

Figure 3 is an elevation of a modified form of the apparatus, parts being broken away and in section;

Figure 4 is a view similar to Figure 3 but showing another modification;

Figure 5 is a view partly in vertical section and partly in side elevation showing a further modification;

Figure 6 is a partly sectional plan view of the invention in the form shown in Figure 5.

Referring at first to the form of the in-

vention shown in Figures 1 and 2 of the drawings the numeral 10 indicates the floor of a room or compartment in which the fibers are to be bedded, and 11 indicates the ceiling of said room. Supported on the floor and in practice approximately centrally in the room, I provide a standard 12 rigidly secured at its lower end as for example by means of a socket 13 on a base 14 bolted to the floor. At the upper end of the standard 12 and extending above the same is a vertical shaft 15 journaled at its lower end in a bearing 16. The upper end of the standard 12 has an enlarged fitting or housing 17 at the upper end of which, at the interior, is a fixed bearing ring 18 within which turns a coating bearing ring 19 on a table or revolving support 20, said support 20 being rigid with the shaft 15. The shaft 15 may be driven in any suitable manner, there being shown in Figure 1 a bevel wheel 21 thereon meshing with which is a bevel pinion 22 on a drive shaft 23 here shown as having a drive pulley 24 adapted to be belted to any convenient prime mover (not shown). The feed pipe 25 is disposed horizontally and braced in the present example from the ceiling 11 by brackets 26, 27. The outlet end 28 of feed pipe 25 is downwardly disposed and communicates with a discharge pipe 29 rigidly secured to the revolving support 20 as by bolts 30. The numeral 31 indicates a balance weight secured to the support 20. The pendent outlet end 28 and the discharge pipe 29 telescope.

In my patent above referred to the upwardly extending outlet end 32 of the revolving discharge pipe 29 affords a direct outlet for the fiber and in the patented construction deflector means is shown as employed above the outlet 32. In my present invention I provide for a laterally deflected discharge of the fiber escaping from the outlet 32 for which purpose in the form shown in Figure 1 a T-shaped terminal fitting 33 is mounted upon the outlet 32 and is adapted to turn thereon, the numeral 34 indicating a bearing for said fitting. The fitting 33 is shown as adapted to be oscillated for which purpose a yoke 35 is attached to the T-head of the fitting 33 as indicated as at 36, and the opposite end of said yoke is secured to a crank pin 37 on a disk 38 rigid with which is a bevel pinion 39 on a short shaft 40 stepped in a bearing 41 on a base

plate 42 rigid with the discharge pipe 29 at the top. Meshing with the bevel pinion 39 is a pinion 43 on a horizontal shaft 44 turning in bearings 45 on the base plate 42. The shaft 42 is driven through the medium of a pinion 46 thereon meshing with a bevel pinion 47 on a collar 48 secured to the pendant outlet 28 of feed pipe 25.

Being discharged from the fitting 33 the fibers will escape laterally instead of being directed vertically from the terminal of the discharge pipe 29 as in my patented construction. The lateral discharge of the fibers causes them to be thrown outward an increased distance so that a large room can be employed and a large bed of the fiber formed. In addition a more thorough mixing of the fiber results from the turning movement imparted to the fitting 33 relatively to the upwardly directed outlet 32 of discharge pipe 29. Thus, it will be seen that as the support 20 turns with the shaft 15 about the axis of said shaft the yoke 35 by reason of the described train of gearing will be given an oscillatory movement causing an effective distribution and mixing of the fibers to be brought about.

In Figure 3 the standard 12 is indicated as well as the enlargement 17, shaft 15 and bearing 16, pinions 21, 22 and shaft 23. The table 120 corresponds essentially with the table 20 and the discharge pipe 129 with its vertically directed discharge terminal 132 corresponds substantially with the discharge pipe 29. A feed pipe 128 extends directly downward through the ceiling 111 and enters the discharge pipe 129. The fitting 133 is an L-fitting turning on a bearing 134 and affording a lateral outlet for the final escape 40 of the fibers. Said fitting is given a continuously revolving movement on the terminal 132 of the discharge pipe 129 through the medium of a ring gear 135 meshing with which is a pinion 139 on a shaft 144 extending in bearings 145 rigid with the base plate 142 on the discharge pipe 129. The opposite end of said shaft 144 has a pinion 146 meshing with a pinion 147 on a collar 148 on the feed pipe 128. The numeral 131 indicates the balance weight on the table or support 120.

In the form shown in Figure 4 the feed pipe 125 has a depending terminal 228 communicating with the upturned receiving end of the discharge pipe 229, the outlet end 232 of said discharge pipe being directed downwardly and communicating with an L-fitting 233 at the under side of the support 220, said fitting 233 discharging laterally. The drive train, Figure 4, for turning the fitting 233 on the discharge pipe 229 in addition to the planetary movement of said fitting about the axis of the shaft 15 is produced by a ring gear 235 on said fitting meshing with which is a pinion 239 on a shaft 244 extending in

hanger bearings 245 depending from the under side of the support 220. The opposite end of shaft 244 has a pinion 246 meshing with a fixed ring gear 247 on the enlargement 117 corresponding with the enlargement 17. Obviously, the fitting 233 will be given turning movement about its own vertical axis in addition to its planetary movement with the discharge pipe 229, through the described train of gearing.

In Figures 5 and 6 the numerals 15 and 17 indicate the described parts bearing these numbers. In said figure the feed pipe 328 passes directly downward and communicates directly with the horizontal discharge pipe 329 corresponding with the discharge pipes 29, 129 and 229. The terminals 332 of the discharge pipe 329 are directed laterally in opposite directions in the general plane of the pipe so that the blast of air by which the fibers are directed from the feed pipe 328 through the discharge pipe 329 will by reaction give a turning movement to said discharge pipe about the axis of the shaft 15. On the terminals 332 are fittings 333 rockably mounted, said fitting overlapping the terminal 332 on spherical lines, the curvature of which is struck from the center of the pivot 336 securing said fitting to said terminal 332. To the pivot 336 is secured a rocker arm 335 to which a connecting rod 350 is pivoted, at one end, the opposite end of said connecting rod having connection with a crank pin 337 on a disk 338 rigid with which is a pinion 339 on a shaft 340, said pinion 339 corresponding with the pinion 39. The pinion 339 meshes with a drive pinion 343 on a shaft 344 which also has a pinion 346 meshing with a ring gear 347 on a collar 348 rigid with the feed pipe 328. The arrangement of Figures 5 and 6, it will be seen, is such that the discharge pipe 329 will be turned about the axis of the shaft 15 through the medium of said shaft and by reason of the re-action of the air blast escaping from the fittings 333 in opposite directions. The fittings 333 will be carried about the axis of the shaft 15 and in addition the train of gearing described will cause said fittings to be oscillated about the pivot 336. The numeral 320 indicates the table or support in Figures 5 and 6.

In all the forms described it will be seen that the final escape of the fiber is in a lateral direction and not vertically; also in all instances the terminal fittings through which the fibers are permitted to escape are given a turning movement on the discharge pipe to variously direct the fibers outwardly.

I would state in conclusion that while the illustrated examples constitute practical embodiments of my invention, I do not limit myself strictly to the exact details herein illustrated, since, manifestly, the same can be considerably varied without departure

from the spirit of the invention as defined in the appended claims.

Having thus described my invention, I claim:

5. 1. In a mixer of the class described, a turnable discharge pipe, means to cause a movement of fibers therethrough, a fitting on said pipe and forming the end thereof, said fitting presenting a lateral discharge
- 10 opening, constituting the outlet from which the fibers issue from said pipe and means to give turning movement to said fitting relatively to the discharge pipe.
- 15 2. In a mixer of the class described, a turnable discharge pipe, means to cause a flow of fiber through said discharge pipe, and a terminal fitting on said discharge pipe opening laterally for escape of the fibers, said fitting forming the end of the pipe and constituting the outlet from which the fibers may issue from the pipe in a direction laterally outward.
- 20 3. In a mixer of the class described, a turnable discharge pipe, means to cause a

flow of fiber through said discharge pipe, 25 and a terminal on said discharge pipe opening laterally for escape of the fibers, said fitting forming the end of the pipe and constituting the outlet from which the fibers may issue from the pipe in a direction laterally outward together with means to give turning movement to said terminal.

4. A mixer of the class described including a feed pipe having a vertical outlet end, 30 downwardly disposed, a laterally disposed pipe to which the first pipe delivers, said second pipe having a vertical outlet end, a support mounting the second pipe, means to turn said support about an axis corresponding with the axis of the outlet end of the feed pipe, a fitting turnably mounted on the outlet end of the second mentioned pipe, a fixed gear element co-axial with the outlet end of the feed pipe, and drive means for turning said fitting on the second mentioned pipe, said drive means engaging and adapted 35 to travel about said fixed gear element.
